(57) **CLAIM**

(21) Appl. No.: **29/144,495**

I claim the ornamental design for a weaver base adapter set
for ruger style firearms, as shown and described.

(22) Filed: **Jul. 5, 2001**

DESCRIPTION

(51) **LOC (7) Cl. 22-01**
(52) **U.S. Cl. D22/110**
(58) **Field of Search** D22/100, 108,
D22/109, 110, 199; 42/70.01, 124, 127

FIG. 1 is a perspective view of a weaver base adapter set for
ruger style firearms showing my new design.

FIG. 2 is a front elevational view thereof; the rear eleva-
tional view being a mirror image of the front.

FIG. 3 is a left side elevational view thereof.

FIG. 4 is a right side elevational view thereof.

FIG. 5 is a top plan view thereof.

FIG. 6 is a bottom plan view thereof; and,

FIG. 7 is an enlarged view showing the detail of the area
denoted by (7) in FIG. 1.
